SAFETY KEEPER PLATE

Thomas J. Dugan, P.O. Box 31356, 3019 N. Main St.,
Alhambra, Calif. 90031

Filed Sept. 24, 1969, Ser. No. 19,278

Term of patent 14 years

Int. Cl. D8—03

U.S. Cl. D8—117

FIG. 1 is a perspective view of the safety keeper plate in the position it would occupy on a door jamb, shown in broken lines for illustrative purposes only;

FIG. 2 is a second perspective view of the safety keeper plate;

FIG. 3 is a front elevational view of the keeper plate;

FIG. 4 is a rear elevational view of my design;

FIG. 5 is a first side elevational view of the keeper plate;

FIG. 6 is a second side elevational view of the keeper plate; and

FIG. 7 is a top plan view of the keeper plate.

I claim:

The ornamental design for a safety keeper plate, as shown and described.
